(57) CLAIM

The ornamental design for a carrying case, as shown and described.

DESCRIPTION

FIG. 1 is a front elevation view of a carrying case, the opposite side being a mirror image thereof.

FIG. 2 is a top elevation view thereof.

FIG. 3 is a bottom elevation view thereof; and,

FIG. 4 is a front perspective view thereof.

The broken lines shown in the drawings show portions of the carrying case which form no part of the claimed design.

1 Claim, 3 Drawing Sheets
